INTERLOCKING SHINGLE

David B. Ronzone, Wilmington, Del., assignor to
Commonwealth Roofing Corporation, Wilming-
ton, Del.

Application September 24, 1948, Serial No. 50,959

1 Claim. (Cl. 108—7)

1

The present invention relates to a new and improved form of shingle of the interlocking type.

The improved shingle of this invention comprises a rectangularly shaped shingle having locking tabs and cooperating locking slots wherein these locking tabs and slots are wholly confined within the boundaries of the shingle.

Heretofore, shingles of this nature have had slots formed in the body thereof, said slots extending inwardly from the edges of the shingle to define the locking tabs and the cooperating locking slots. This often results in a number of imperfect shingles due to the fact that the tabs are easily bent and torn either during assembling of the shingles on the roof or after the shingles have been interlocked.

In the present invention, the locking tabs and locking slots are formed inwardly from the edges of the shingle thus producing an interlocking shingle having an uninterrupted continuous edge.

A further important feature of the present invention is the provision of a shingle having pre-formed nailing holes therein to provide a guide for properly laying the shingles. One of the pre-formed holes is so related with respect to the locking slot as to more readily permit entrance of a locking tab in said slot after a nail has been driven through said hole.

A still further feature of the present invention is the provision of cooperating portions on the shingle to protect the roof against side-lash from rain or wind.

The present shingle may be made of metal or of composition, is relatively simple to manufacture, can be assembled with a minimum amount of labor, and when applied to a roof presents a most attractive appearance.

Other objects and advantages of the present invention will be apparent from the following detailed description taken in connection with the accompanying drawing wherein:

Figure 1 is a plan view of a preferred embodiment of the shingle forming the subject matter of the present invention.

Figure 2 is a fragmentary plan view of a portion of a roof formed by laying the shingles of Figure 1.

Figure 3 is an exploded view showing the manner of assembling two shingles.

Figure 4 is an enlarged sectional view taken along the line 4—4 of Figure 2.

Figure 5 is a plan view of a slightly modified form of shingle.

Referring to the drawing in detail, Figure 1 illustrates a preferred embodiment of the inven-

2

tion wherein the shingle is formed of aluminum or other equivalent sheet metal. The shingle is of generally rectangular configuration and constitutes a body portion 10 bounded by the edges 11, 12, 13 and 14. A pair of slots 15 are stamped out of the metal shingle and constitute the locking slots. The locking tabs 16 are formed by cutting U-shaped slots in the shingle as indicated by numeral 17. The locking tabs 16 are one inch wide and the slots are approximately one inch and one sixteenth wide in order to receive the tabs.

As seen in Figure 1, a pair of holes 18 are stamped out of the shingle, adjacent the slots 15 and receive the usual nail for attaching the shingle to a roof. An additional nail hole 19 is provided midway of the shingle adjacent edge 12 for properly lining up the shingles as will more clearly appear as the description proceeds.

20 In order to insure against side-lash, the shingle is provided with a pair of V-shaped grooves which may be pressed out of the shingle during the stamping operation. One of the grooves, designated by the numeral 20 is located adjacent 25 the slots 15 and the second groove 21 is formed at the edge 13. The grooves do not extend entirely across the width of the shingle so as not to interfere with the proper overlapping of adjacent rows of shingles as seen in Figure 2.

30 The shingles may be assembled in interlocked relation in the manner shown in Figures 2, 3 and 4 wherein 22 denotes the roof member to which the shingles are applied and 23 the shingle nails. In assembling the shingles, the singles are laid from 35 left to right beginning in the lower left hand corner of the roof. The first shingle is laid and nails driven through the holes 18. As the nails are driven home, the metal adjacent these holes to the left of the slots 15 is forced downwardly 40 leaving an enlarged slot for receiving the locking tab 16. The next adjacent shingle is then applied by pressing down on the locking tabs and inserting said tabs in the slots 15. The grooves 20 and 21 are so positioned that when the next adjacent shingle is inserted and driven home, the grooves 20 and 21 overlap. In this position, nails are driven through the holes 18 of the next shingle. This operation is continued until the lower row of shingles is assembled.

45 The first shingle of the second row is applied by juxtaposing its lower hole 18 over hole 19 of the first row shingle and continuing the assembly as previously explained. The provision of hole 19, 50 thus insures proper positioning of the second row

55

of shingles. All of the rows of shingles may be assembled in a similar manner.

As described above the invention has been applied to metallic shingles. When using composition shingles, the upper locking tab and cooperating slot may be eliminated as seen in Figure 5, which shows a single locking tab 24, locking slot 25, and nail holes 26 and 27. These shingles are applied to the roof in the same manner as the metallic shingles.

Although the present embodiment of the invention is illustrated in connection with roofing shingles, it will be readily apparent that the present invention may also be applied to siding shingles.

It will be noted that the construction herein shown and described is well adapted to accomplish the objects of the present invention. It will be understood that minor changes may be made in the present invention without departing from the spirit thereof. Therefore, I do not wish to be limited precisely to the construction herein shown except as may be required by the appended claim considered with reference to the prior art.

Having thus described the invention, what is claimed is:

An interlocking shingle comprising a body

portion of general rectangular configuration having a forward edge, transverse edges and a rear edge, slots formed in the body portion adjacent the forward edge and spaced inwardly of the edges of the shingle, cooperating locking tabs formed in the body of the shingle adjacent the rear edge and spaced inwardly of the edges of the shingle, preformed nailing holes provided in the body portion adjacent the slots and to the rear thereof, a preformed hole formed in the body of the shingle adjacent an upper transverse edge and midway of the length of the shingle, and raised ridges formed in the shingle extending partially across the width of the shingle, one of said ridges formed adjacent the slots and the other ridge formed at the rear edge of the shingle.
